UNITED STATES PATENT OFFICE.

JOHN B. SPERRY, OF AURORA, ILLINOIS, ASSIGNOR TO THE AMERICAN WELL WORKS,
OF AURORA, ILLINOIS, A CORPORATION OF ILLINOIS.

PUMPING APPARATUS.

1,170,574.

Specification of Letters Patent. Patented Feb. 8, 1916.

Application filed January 27, 1913. Serial No. 744,430.

To all whom it may concern:

Be it known that I, JOHN B. SPERRY, a citizen of the United States, residing at Aurora, in the county of Kane, in the State 5 of Illinois, have invented certain new and useful Improvements in Pumping Apparatus, of which the following is a specification, reference being had to the accompanying drawings.

10 This invention relates to pumping apparatus and particularly to that class of pumps in which the raising of the water is effected through the medium of a rotating vertical shaft extending down into the well. In 15 pumping apparatus of this type it is highly important that the power be applied to the vertical shaft to the best advantage without any side draft upon the shaft itself.

It is one of the objects of this invention to 20 provide a construction by which power may be transmitted to the shaft through a belt without there being any side draft on the shaft.

It is another object of my invention to 25 provide improved means for the lubrication of such a construction.

It is another object of this invention to 30 provide guide rollers for holding the driving belt in proper position relative to the shaft pulley, the guide rollers and the means for supporting the same being arranged in such a manner as to render the belt easily removable therefrom without unlacing.

It is one of the objects of my invention 35 to provide means insuring against the forcing of the water and sand upward along the pump shaft into the bearings for said shaft. This is accomplished, in the construction shown, by providing a packing between the water lifting elements and the bearing for the shaft immediately above them, by providing an opening from the shaft to the well casing above the packing and below the bearings for the shaft, and 40 by providing for a small head of water surrounding the shaft above said packing serving as a water-seal.

It is another object of my invention to 45 provide improved means for lubricating the bearings of the pump shaft by means of pure water supplied from any suitable source from the surface or by means of the water

being pumped, the same being thoroughly filtered or strained before being permitted to enter the shaft casing. 55

It is another object of this invention to improve apparatus of this description in sundry details hereinafter pointed out.

The means by which I have accomplished these objects are illustrated in the accompanying drawings and are hereinafter specifically described. That which I believe to be new and desire to cover by this application is set forth in the claims.

In the drawings, Figure 1 is a central vertical section through the upper portion of the pumping apparatus; Fig. 2 is a view of the upper end of the discharge head as seen from the left in Fig. 1, showing the construction of the support for the guide rollers; Fig. 3 is an enlarged detail through one side of the drive pulley mounted on the upper end of the pump shaft; Fig. 4 is a central vertical section through the apparatus at the bottom of the well, showing the runners by which the water is lifted and showing the bearing located just above the lifting devices. This figure also shows one of the intermediate bearings for the pump shaft; and Fig. 5 is an enlarged detail, being 75 a central vertical section through the bearing immediately above the water raising elements.

Referring to the several figures of the drawing, 10 indicates a base-plate fixed in 85 position upon a base 11 built about the upper end of the well casing 12.

13 indicates the discharge head, leading from one side of which there is a suitable discharge pipe 14. 90

15 indicates the pump shaft mounted on the discharge head 13 by means of a roller bearing 16 of any suitable type. As shown in Fig. 1, the bearing 16, together with the flanges 17 upon which it is supported, completely closes off a portion of the discharge head 13 at its upper end providing an oil well 18.

19 indicates a discharge pipe, leading from the bearing 16, being provided on its outer 100 end with an oil-gage 20 and a stop-cock 21.

22 indicates a stuffing box surrounding the pump shaft 15 immediately below the roller bearing 16, an outlet port being provided

- for permitting the escape of any water that may be forced upward through the stuffing box 22 so that such water shall not contact the bearing, such port being shown in Fig. 5 1 as closed by a screw-threaded plug 22^a.
- 23 indicates a head mounted upon the upper end of the discharge head 13, said head 23 terminating at its upper end with two annular flanges 24—25.
- 10 26 indicates a pulley provided with a hub 27 which is fixedly secured upon the upper end of the shaft 15 by means of set screws or in any other suitable manner.
- 15 28 indicates an annular flange depending from the hub 27 of the pulley, being adapted to extend downward between the flanges 24 and 25 of the head 23.
- 20 29 indicates a roller bearing inserted between the flange 25 of the head 23 and the flange 28 of the pulley 26, said roller bearing comprising, as is best shown in Fig. 3, a hard steel cylinder 29^a fixedly mounted in the flange 28, a second hard steel cylinder 29^b fixed upon the flange 25, and a plurality 25 of anti-friction rollers 29^c. By reason of this construction, when the bearing 29 becomes worn, it can be removed and a new one substituted. As is shown in Fig. 1 the annular flange 25 is out of contact with the shaft 15 so that when the belt, shown in dotted lines in Fig. 1 and indicated by the numeral 30, is applied to the pulley the side draft is taken up by the head 23 without in any way affecting the central position of the shaft 15.
- 30 35 31 indicates an oil tank connected by means of a pipe 32 to the oil well 33 formed by the flanges 24—25. By this construction and arrangement the oil well 33 is adapted to be kept full of oil, thus insuring a perfect 40 lubrication of the bearing 29, a circulation of the oil in the chamber through the bearing 29 being insured by the provision of openings 28^a through the flange 28 near the upper end of the chamber 33. Oil is also adapted 45 to flow over the upper end of the flange 25 into the oil well 18, thus keeping the bearing 16 flooded with oil, as will be readily understood.
- 50 34 indicates a bracket rising from one side of the head 23.
- 35 indicates flanged rollers journaled in any suitable manner at the upper and the lower ends of said bracket 34. These rollers 35 serve to hold the belt 30 in its proper 55 position upon the pulley 26 with its center located approximately opposite the middle point of the bearing 29. When it is desired to remove the belt 30 from the pulley 26 this can be accomplished very readily without 60 unlacing the belt when the belt has been removed from the drive wheel of the engine, as will be readily understood.
- 65 As best shown in Fig. 1, the lower end of the discharge head 13 has secured to it a water discharge casing 36, which communi- cates with and forms a continuation of the lower portion of said discharge head.
- 37 indicates a shaft casing supported by arms 38 extending inward from the water discharge casing 36. As shown in Fig. 1, the shaft casing 37 extends upward to a point above the lower end of the discharge pipe 14. A flange 39 provided with a stuffing box 40, surrounding said casing 37, separates the open upper end of the casing 37 from communication with the water discharge casing 36.
- 70 As will be readily understood, the shaft 15 is adapted to be made in sections connected together by coupling sleeves 41 of any approved type. The water discharge casing 36 and the shaft casing 37 are also adapted to be made in sections coupled together by the means shown at the upper end of Fig. 4. In this figure 42—43 indicate 75 flanges adapted to be screw-threaded upon the lower and the upper ends, respectively, of the abutting sections of the casing 36, said sleeves being connected together by bolts or by any other appropriate means. 80 44 indicates a sleeve having screw-threaded connection with the adjoining ends of the sections of the casing 37, said sleeve 44 being supported by arms 45 carried by the flanges 42—43. The sleeve 45 is provided with a 85 bushing 46 composed of argota, or other close grained wood, or other suitable material. In the lower end of Fig. 1 the sleeve supported by the arms 38 and supporting the bearing for the shaft 15 is indicated by 90 47, and the bushing carried by said sleeve is indicated by the numeral 48. As shown in Fig. 4, the lower end of the water discharge casing 36 has connected to it, by means of bolts or in any other suitable manner, a 95 pump bearing casing 49. Below this casing 49 are successively connected in series a pump shell 49^a, a second pump shell 49^b, and a bottom bearing head 50 which by means of webs 51 holds in position the bottom bearing 52 of the shaft. To the lower end of the bearing head 50 is attached the upper end of the suction pipe 53.
- 100 The lifting elements of the pump are old and well-known in the art. They comprise 115 hubs 54 and 55 upon the shaft 15 provided with runners 56 which rotate with the shaft between the walls of the pump shells 49^a—49^b and the cone-shaped parts 57 which are supported by means of ribs 58 from the surrounding casings. As best shown in Fig. 4, the hubs 54—55 are spaced upon the shaft 15 by means of a plurality of bushings. A bushing 15^a has its upper end resting against a shoulder formed in the shaft, against the 120 lower end of which bushing the hub 54 is adapted to bear. A second bushing 15^b having its upper end resting against the hub 54 serves to space the hub 55 away from the hub 54, and a third bushing 15^c, 130

which is secured in position by means of lock nuts 15^a which are screw-threaded upon the lower end of the shaft 15, serves to hold the parts snugly together. The 5 three bushings and the two hubs 54—55 are caused to rotate with the shaft 15 by feathers 54^a and 55^a, as will be readily understood. The bushings 15^a—15^b—15^c are preferably formed of brass, thus 10 serving not only to position the runners 56 upon the shaft but also providing bearing surfaces of extreme durability which will not readily corrode.

The upper one of the two cone-shaped 15 parts 57 is provided with a packing-box 59 which is calculated to prevent the forcing of any water and sand upward along the shaft into the bearing at the lower end of the water discharge casing 36. In order that 20 any water and sand which might be forced upward through the packing-box 59 may be prevented from being forced into the bearing just above it, an opening 60 is provided about the shaft 15 communicating 25 with the well casing outside of the water discharge casing by means of diagonally positioned discharge ports 61.

60^a indicates a flexible washer surrounding the shaft 15 above the packing box 59 30 and fitted tightly to the bushing 15^a. This washer serves to prevent air from entering the pump casing from the well through the ports 61, and also assists in preventing sand from being forced upward along the shaft 35 out of the pump casing into the bearing above, being very efficient on account of its tight fit upon the bushing 15^a. The shaft casing 37 also ends and is connected to the pump bearing casing 49 at the same point 40 as that at which the casing 36 is connected, the lower end of said casing 37, in the construction shown, being screw-threaded upon a sleeve 62 forming part of the bearing casing 49. Said sleeve 62 is provided with a 45 bushing 63, composed of argota or other suitable material, forming a bearing for the shaft 15.

Referring again to Fig. 1, 64 indicates a pipe leading into the chamber 65 between 50 the flange 39 and the stuffing box 22 in the discharge head 13. Said pipe 64 is provided at its upper end with a funnel 66 whereby water can be poured into said chamber 65, as will be hereinafter described, such water 55 being adapted to flow over the upper end of the casing 37 into the interior thereof.

67 indicates a screen of very fine mesh covering openings in the casing 37. As will be readily understood when the pump is 60 operating and is lifting water a limited amount of the water being lifted will be filtered or strained through the strainer 67 into the casing 37. This water serves to lubricate the bearing between the shaft 15 65 and the wooden sleeve 48. The sleeve 47 is

provided with a duct 68 extending vertically therethrough whereby the water which is admitted into the casing 37 either through the strainer 67 or from the chamber 65 is permitted to pass down inside the casing 37 70 to lubricate the several bearings for the shaft 15.

Referring now to Fig. 4 it will be seen that the sleeves 44 are provided with ducts 69 which pass vertically through said sleeves permitting the water to pass downward the full length of the casing 37. The sleeve 62 at the bottom of the casing 37 is provided with a duct 70 passing vertically through the sleeve, opening at its lower end 80 into the opening 60, which is thus kept filled with water during the operation of the pump up to the level determined by the lower edge of the upper end of the discharge ports 61, thus providing a permanent water 85 seal as above described. The sleeve 62 is also provided with a duct 71 leading partially through said sleeve 62, connected at its lower end by means of a short section of pipe 72 and a suitable duct through a portion of the bearing-casing 49 with a pipe 73, which extends downward within the well casing 12, past the water lifting elements to the lower bearing 52. The lower bearing 52 is provided with a cap 52^a screw-threaded 90 upon its lower end, as best shown in Fig. 4. 74 indicates a bushing of argota, or other suitable material, forming a bearing surface with the bushing 15^c such as to be suitable for lubrication by means of water. The 100 bushing 74 is held against turning with the shaft by means of a set-screw 75. The upper end of the bearing 52 is closed by means of packing 76 held in position by a suitable cap 77.

105 It will be understood that when the pump has been standing for some little time without being operated water can be poured into the funnel 66 in order to lubricate the bearings throughout the system before the pump is started into operation. When thereafter the pump is in operation the system I have just described insures there being an abundance of water for lubricating purposes and for the purpose of maintaining a water seal 110 in the chamber 60, such water being admitted 115 to the casing 37 through the strainer 67.

I do not wish to claim broadly the use of filtered or strained water for lubricating the bearings of the pump shaft nor to claim the 120 invention disclosed by the application of Chapman and Chapman Serial No. 482,517, filed March 10, 1909.

What I claim as my invention, and desire to secure by Letters Patent, is,—

125 1. In a pumping apparatus, the combination of a water discharge casing, a pump shaft extending therethrough, a pulley fixed upon said shaft and having a bearing on said water discharge casing, a bearing for 130

said shaft separated from said water discharge passage, and a screen covering a port between said shaft and said water discharge passage adapted to filter water permitted to 5 pass to said bearing for lubricating purposes.

2. In a pumping apparatus, the combination of a water discharge casing, a pump shaft extending therethrough, a pulley fixed 10 upon said shaft and having a bearing on said water discharge casing, a shaft casing located in said water discharge casing separating said shaft therefrom, bearings for said shaft in said shaft casing, and a screen 15 covering a port in the wall of said shaft casing below the level of the water about said shaft casing during the pumping operation, said screen being adapted to filter water permitted to pass into said shaft casing for the purpose of lubricating said bearing, 20 each of said bearings being provided with a duct therethrough whereby the screened water is permitted to pass downward along the shaft inside of the shaft casing for lubricating the bearings.

3. In a pumping apparatus, the combination of a stationary frame, a bearing sleeve fixed thereon, a vertical shaft extending loosely through said bearing sleeve, driving means journaled upon said bearing sleeve and connected with said shaft for rotating the shaft serving to hold the shaft out of contact with the bearing sleeve, and pumping means connected with said shaft.

35 4. In a pumping apparatus, the combination of a water discharge casing, a shaft extending therethrough, a shaft casing located in said water discharge casing separating said shaft therefrom, means for rotating said shaft, means operatively connected with said shaft for forcing water upward through said water discharge casing, bearings for said shaft in said shaft casing, another bearing for said shaft below said 45 water-raising elements, means for supplying a lubricating fluid to said shaft casing whereby it is directed to the bearings in said casing, each of said last-named bearings being provided with a duct therethrough 50 whereby the lubricating fluid is permitted to pass downward along said shaft casing, and means connecting the lower end of said shaft casing with said lower bearing whereby the lubricating fluid is permitted to pass thereto.

55 5. In a pumping apparatus having a water discharge passage, the combination of a shaft rotatable in said passage, a plurality of bearings for said shaft separated from said water discharge passage, and a screen covering a 60 port between said shaft and said water discharge passage above said bearings adapted to filter water permitted to pass downward to said several bearings for lubricating purposes.

65 6. In a pumping apparatus, the combina-

tion of a water discharge casing, a shaft extending therethrough, a shaft casing located in said water discharge casing separating said shaft therefrom, means for rotating said shaft, means operatively connected with said shaft for forcing water upward through said water discharge casing, a bearing for said shaft in said shaft casing, and a screen covering a port in the wall of said shaft casing near the upper end of the water discharge casing below the level of the water about said shaft casing during the pumping operation, said screen being adapted to filter water permitted to pass into said shaft casing for the purpose of lubricating said bearing.

70 7. In a pumping apparatus, the combination of a water discharge casing, a shaft extending therethrough, a shaft casing located in said water discharge casing separating said shaft therefrom, means for rotating said shaft, means operatively connected with said shaft for forcing water upward through said water discharge casing, a plurality of bearings for said shaft in said shaft casing, each of said bearings having a duct therethrough, and a screen covering a port in the wall of said shaft casing below the level of the water about said shaft casing during the pumping operation, said screen being adapted to filter water permitted to pass into said shaft casing for the purpose of lubricating said bearings.

75 8. In a pumping apparatus, the combination of a water discharge casing, a shaft extending therethrough, a shaft casing located in said water discharge casing separating said shaft therefrom, means for rotating said shaft, means operatively connected with said shaft for forcing water upward through said water discharge casing, a bearing for said shaft in said shaft casing, said bearing having a duct therethrough, another bearing for said shaft below said water raising elements, means connecting the lower end of said shaft casing with said lower bearing whereby a lubricating fluid is permitted to pass thereto, and a screen covering a port in the wall of said shaft casing below the level of the water about said shaft casing during the pumping operation, said screen being adapted to filter water permitted to pass into said shaft casing for the purpose of lubricating said bearings.

80 9. In a pumping apparatus, the combination of a water discharge casing, a shaft extending therethrough, means for rotating said shaft, means operatively connected with said shaft for forcing water upward through said water discharge casing, a packing-box about said shaft to prevent the water being forced upward along said shaft instead of through the water discharge passage, a recess about said shaft above said packing-box,

- a port leading diagonally upward from said recess into the well outside of said water discharge casing, and means for supplying water to said recess to serve as a water seal 5 in connection with said packing-box.
10. In a pumping apparatus, the combination of a water discharge casing, a shaft extending therethrough, a shaft casing located in said water discharge casing separating said shaft therefrom, means for rotating said shaft, means operatively connected with said shaft for forcing water upward through said discharge casing, a bearing for said shaft in said shaft casing, a packing-box about said shaft to prevent the dirty water from being forced upward along said shaft into said bearing instead of through the water discharge passage, a recess about said shaft above said packing-box 15 and below said bearing, a port leading diagonally upward from said recess into the well outside of said water discharge casing, and a screen covering an opening from said water discharge casing into said shaft casing adapted to filter water permitted to pass down said shaft casing and through a duct into said recess about the shaft to serve as a water seal in connection with said packing-box.
- 20 11. In a pumping apparatus, the combination of a water discharge casing, a shaft extending therethrough, means for rotating said shaft, means operatively connected with said shaft for forcing water upward through said water discharge casing, a recess about said shaft above said water lifting elements, a port leading diagonally upward from said recess into the well outside of said water discharge casing, a flexible washer mounted about said shaft in said recess and adapted to rotate with the shaft, and means for supplying water to said recess to serve as a water seal in connection with said washer.
- 25 12. In a pumping apparatus, the combination of a water discharge casing, a shaft extending therethrough, means for rotating said shaft, means operatively connected with said shaft for forcing water upward through said water discharge casing, a recess about said shaft above said water lifting elements, a port leading diagonally upward from said recess into the well outside of said water discharge casing, a flexible washer mounted 30 about said shaft in said recess and adapted to rotate with the shaft, and means for supplying water to said recess to serve as a water seal in connection with said washer.
- 35 13. In a pumping apparatus, the combination of a water discharge casing, a shaft extending therethrough, means for rotating said shaft, means operatively connected with said shaft for forcing water upward through said water discharge casing, a recess about said shaft above said water lifting elements, a port leading diagonally upward from said recess into the well outside of said water discharge casing, a flexible washer mounted 40 about said shaft in said recess and adapted to rotate with the shaft, and means for supplying water to said recess to serve as a water seal in connection with said washer.
- 45 14. In a centrifugal pumping apparatus the following elements in combination, a centrifugal pump, a line shaft for the pump, a discharge duct from the pump to the top of the well through which said shaft passes, a shaft casing for closing said shaft off from the rising column of water in said discharge duct, and means for effecting a circulation of well water down inside such shaft casing.
- 50 15. In a pumping apparatus, the combination of a water discharge casing, a shaft extending therethrough, means for rotating said shaft, means operatively connected with said shaft for forcing water upward through said water discharge casing, a recess about said shaft above said water lifting elements, a port leading from said recess into the well outside of said water discharge casing, and means for purifying a portion of the water pumped and delivering it into said recess.
- 55 16. In a pumping apparatus, the combination of a water discharge casing, a shaft extending therethrough, a shaft casing located in said water discharge casing separating said shaft therefrom, means for rotating said shaft, means operatively connected with said shaft for forcing water upward through said water discharge casing, a bearing for said shaft below said water raising elements, and means for purifying a portion of the water pumped and delivering it to said bearing for lubricating it.
- 60 17. In a pumping apparatus, the combination of a water discharge casing, a shaft extending therethrough, a shaft casing located in said water discharge casing separating said shaft therefrom, means for rotating said shaft, means operatively connected with said shaft for forcing water upward through said water discharge casing, a bearing for said shaft below said water raising element, means connecting said shaft casing with said bearing whereby lubricating fluid is permitted to pass from said shaft casing to said bearing, and means for purifying a portion of the water pumped and delivering it into the shaft casing.
- 65 18. In a pumping apparatus, the combination of a water discharge casing, a shaft extending therethrough, a shaft casing located in said water discharge casing separating said shaft therefrom, means for rotating said shaft, means operatively connected with said shaft for forcing water upward through said water discharge casing, a bearing for said shaft in said shaft casing, another bearing for said shaft below said

water raising elements, means connecting said shaft casing with said second-named bearing whereby lubricating fluid is permitted to pass from said shaft casing to said 5 second-named bearing, and means for purifying a portion of the water pumped and delivering it into the shaft casing for lubricating said bearings.

19. In a pumping apparatus, the combination of a water discharge casing, a shaft extending therethrough, a shaft casing located in said water discharge casing separating said shaft therefrom, means for rotating said shaft, means operatively connected with said 10 shaft for forcing water upward through said water discharge casing, a port leading from the lower end of said shaft casing, and means for purifying a portion of the water pumped and delivering it into said shaft casing near the upper end of said water discharge casing.

15

fying a portion of the water pumped and 20 delivering it into said shaft casing.

20. In a pumping apparatus, the combination of a water discharge casing, a shaft extending therethrough, a shaft casing located in said water discharge casing separating said 25 shaft therefrom, means for rotating said shaft, means operatively connected with said shaft for forcing water upward through said water discharge casing, a port leading from the lower end of said shaft casing, and 30 means for purifying a portion of the water pumped and delivering it into said shaft casing near the upper end of said water discharge casing.
